UNITED STATES PATENT OFFICE.

JOSHUA KING NORTHRUP, OF ELLICOTTVILLE, NEW YORK.

RAIL JOINT.

Application filed November 4, 1927. Serial No. 231,139.

This invention relates to improvements in rail joints and has for its chief object to provide a simple, strong and reliable joint of this character which can be effectually and 5 quickly assembled without the use of bolts or similar fastenings.

A further object of the invention is to so organize and construct the parts of the joint that the rails will at all times be maintained 10 in perfect alignment and be prevented from vertical and lateral displacement at their abutting ends.

In the accompanying drawings:—

Figure 1 is a side elevation of the abutting 15 ends of two railroad rails showing my improved joint applied thereto. Figure 2 is a transverse section on line 2—2, Figure 1. Figure 3 is a horizontal section on line 3—3, Figure 1. Figure 4 is a fragmentary longitudinal section on line 4—4, Figure 2. Figure 5 is a fragmentary perspective view of 20 one of the fish plates.

Similar characters of reference indicate 25 corresponding parts throughout the several views.

The numerals 10, 10 indicate the abutting ends of adjoining railroad rails which are to be connected by the improved joint. Telescopically fitted over the base and web of 30 the abutting rail-sections is a chair 11 including a base portion 12 and side walls 13, 13, the chair-base resting at its ends on the ties 14 and the side walls thereof extending inwardly over the rail-base and thence upwardly along the opposite sides of the rail-web and terminating at their upper edges a suitable distance below the head of the rail. The side walls of this chair, as shown in Figure 2, are spaced from the contiguous sides 35 of the rail-base and its web, and occupying these resulting L-shaped spaces are flanged fish plates 15, 15 having a series of locking 40 studs 16 thereon which are adapted to engage openings 17 formed in the webs of the abutting rail-sections to prevent longitudinal 45 displacement of the fish plates relative to the rails. The upper edges of the chair side walls 13, 13 are preferably shaped into upwardly-facing longitudinal tongues 18 and 50 the fish plates are provided at their upper ends with heads 19 having longitudinal grooves 20 in their undersides for receiving said tongues in the manner shown in Figure 2. In the assembled position of the joint—

parts, the side walls of the chair 11 and the 55 fish plate heads 19 are substantially flush with the sides of the rail-head. If desired, the heads of the fish plates may be provided at suitable intervals with tongues 21 for interlocking engagement with corresponding 60 recesses 22 in the underside of the rail-head.

By this construction and arrangement of parts, the fish plates are reliably interlocked with the rails against longitudinal displacement and the chair is coupled with the fish 65 plates in a manner to prevent any relative lateral or vertical shifting movements of these parts as well as any depression or separation of the rails. In the assembling of the joint which is accomplished without the 70 use of bolts or special tools, the fish plates are first set in place across the joint of the abutting rail-sections, after which the chair is shifted lengthwise over such plates.

For the purpose of holding the chair 11 75 against longitudinal displacement relative to the rail-sections 10 and the fish plates 15 in one direction, the contiguous side walls of these parts are slightly tapered from one end thereof to the other, so that in applying 80 the chair it is driven over the fish plates in the direction of the arrow shown in Figure 3, to tightly wedge said chair in place. To hold the latter in place against movement in the opposite direction, the overlying 85 flanged portions of the chair and fish plates are provided near their ends with registering openings 23 and 24, respectively, which together form sockets or recesses for receiving anti-creeping members 25, preferably in the form of spring steel locking bars, each shaped to bear at one end against the opposing end wall of the chair-opening 23 and at its other end against the opposing end wall of the fish plate opening 24, thereby 90 locking the chair against movement in the direction of the arrow shown in Figure 4.

To strengthen the base portion 12 of the chair between its ends, it may be provided with an integral, reinforcing rib 26.

In dismembering the joint, the members 25 are first removed, after which the chair is shifted from engagement with the fish plates and the latter disconnected from the rails.

This improved joint, while manifestly simple and durable in construction, can be readily assembled and dismembered, and it

reliably supports and effectually prevents relative movements of the abutting ends of the rail-sections.

I claim as my invention:—

5. 1. A rail joint, comprising a chair for receiving the abutting ends of adjoining rails and including a base section and opposing side walls spaced from the rail-webs, fish plates applied to opposite sides 10 of the rails in the spaces between the rail-webs and the opposing chair-walls, means for holding the fish plates against movement lengthwise of the rails, the contiguous walls of the chair and the fish plates 15 being tapered in one direction and having registering openings therein, and members removably seated in said openings and each bearing at one end against one of the end walls of one opening and at its other end 20 against the opposite wall of the companion registering opening.

2. A rail joint, comprising a chair for receiving the abutting ends of adjoining rails and including a base section and opposing side walls spaced from the rail bases 25 and the rail-webs, fish plates having base-flanges applied to the opposite sides of the rails in the spaces between the chair and the rails, means for holding the fish plates

against movement lengthwise of the rails, the 30 contiguous walls of the chair and the fish plates being tapered in one direction and having registering openings in the overlying base portion of the chair and in the base flanges of said plates, and spring 35 locking bars adapted for insertion in each set of registering openings for engagement at one end with one of such openings and at the other end with the companion opening 40 of a set.

3. A rail joint, comprising fish plates applied to the adjoining ends of abutting rails, the upper ends of said plates having downwardly-facing longitudinal grooves, means for holding the fish plates against movement 45 lengthwise of the rails, a chair applied to the rails over said fish plates and terminating at the upper edges of its side walls in longitudinal tongues arranged to engage said fish plate grooves, the opposing contiguous 50 walls of the fish plates and the chair being tapered to limit the movement of the latter on the fish plates in one direction, and detachable means for locking the chair to said fish plates to prevent its movement in 55 the opposite direction.

JOSHUA KING NORTHRUP.
